UNITED STATES PATENT OFFICE.

JOHN RUDD VAN DYNE, OF SEDALIA, MISSOURI, ASSIGNOR TO CHANNELL CHEMICAL COMPANY, OF CHICAGO, ILLINOIS, A CORPORATION OF ILLINOIS.

DUST-MOP.

1,202,334.

Specification of Letters Patent.

Patented Oct. 24, 1916.

Application filed April 21, 1914. Serial No. 833,418.

To all whom it may concern:

Be it known that I, JOHN R. VAN DYNE, a citizen of the United States, residing at Sedalia, in the county of Pettis and State of Missouri, have invented certain new and useful Improvements in Dust-Mops, of which the following is a specification.

My invention relates to mops, and more particularly to mops in which the mop material or brush portion is detachably secured to a frame or head.

Specifically, the present invention is designed as an improvement over the construction of mop shown in Patent No. 1,081,225, granted to H. L. Feasel, Dec. 9, 1913.

One object of the invention is to simplify and cheapen the construction of the Feasel device without sacrificing any of its advantages.

Another object is to provide a mop head of novel form especially designed to efficiently enter corners and under furniture and the like.

In order that my invention may be readily understood, reference is had to the accompanying drawing, forming part of this specification, and in which,

Figure 1 is a plan view of my improved mop complete; Fig. 2 is a side elevation from the rear of the mop head alone; Fig. 3 is a vertical longitudinal section showing the manner of assembling the parts of my improved mop; and, Fig. 4 is a similar section substantially on the line 3—3 of Fig. 1.

Referring to the drawings in detail, I construct my improved mop head of only three pieces, such pieces comprising a pair of plates or sections A, B, and a coupling or socket member C. Each plate A and B is dish-shaped in section and consists of a flat bottom 1 provided with an upstanding marginal flange 2. This flange is bent first inwardly and then outwardly into concave form so as to provide an annular groove 3, extending around the head.

By reference to Fig. 1, it will be noted that I prefer to make my improved mop head of trapezoidal form having comparatively long parallel front and rear edges, and comparatively short converging ends, the front edge being longer than the rear edge, whereby acute angles are formed at the front corners at each end, as indicated at 4. These angles or corners are particularly effective in cleaning corners of rooms,

and owing to their comparatively great distance from the handle, enable the operator to reach farther under furniture and the like than is possible with other shapes of mop.

The two sections A and B are pivoted together by means of a transversely extending hinge 5, formed below the bottom plate 1, and the rotation of the parts about such hinge is limited by the abutting edges 3^a of the upstanding flanges. When these edges are in engagement the sections A and B are in alinement as shown in Figs. 1 and 4. Around the base of the flange adjacent the bottom 2 may be formed a number of small holes 6, so that oil or the like poured into the dish-shaped head may flow laterally through such openings and impregnate the mop material.

The coupling or socket member comprises a relatively small flat plate 7, from which projects a suitable socket 8, preferably internally screw threaded to receive a handle, (not shown). The plate 7 is rigidly secured, as by rivets 9, to one section, such as A, and extends across the hinge so as to overlie the other section B. A screw stud 10 projects upwardly from the bottom of section B, and is adapted to pass through an opening 11 in the plate 7. A thumb nut 12 is adapted to engage the stud 10, and when screwed down firmly, serves to lock the sections A and B rigidly together in perfect alinement, as shown in Figs. 1 and 4.

The mop is in the form of a ring of fibrous material 14, provided around its upper edge with a flexible binding 13 adapted to lie in the groove 3 formed in the flange 2.

It will be apparent that when it is desired to assemble the parts, the thumb nut 12 is removed and the sections swung about the hinge into some such position as shown in Fig. 3. The flexible binding of the mop is then placed in the grooves at the outer ends of the pivoted sections and by pressing downwardly on the socket member the sections are brought into alinement, as shown in Fig. 4, exerting an expanding toggle action and firmly tensioning the binding 13 in the groove. The binding is most tightly gripped at the points where it passes around the acute angles 4, as indicated at 15 in Fig. 4.

It will thus be seen that instead of employing a dish-shaped plate and a toggle

plate in addition, as in the Feasel construction, I eliminate one of these plates and hinge the dish-shaped plate itself so as to provide a toggle action. In other words, my improved mop head consists of but a single plate formed of two sections, and a socket member which serves to hold the sections in alinement.

While I have shown and described my improved construction in connection with a dish-shaped plate adapted to contain a liquid, it will be apparent that a similar construction, embodying the use of a pair of sections hinged together and bridged by a socket member can be employed in connection with a head formed of a flat or solid block or plate provided with a marginal groove.

What I claim is:

- 20 1. As an improvement in mops, a mop head consisting of a mop engaging plate formed of two articulated sections, and a socket member adapted to bridge the joint between said sections.
- 25 2. As an improvement in mops, a mop head consisting of a mop engaging plate formed of two sections hinged together, a socket member having a part permanently secured to one section and extending across the hinge, and means for detachably con-

necting the other section to said member, whereby said sections are held in alinement.

3. As an improvement in mops, a mop-head made up of a plate divided transversely to form two sections of substantially equal thickness and width, each section being provided along at least one edge, with a marginal groove, said grooves and sections normally lying in the same plane, said sections being unyieldingly and pivotally connected at a point to one side of such plane, and a mop provided with a flexible ringlike binding encircling said sections, lying in said grooves, and tending to maintain the parts in normal position.

4. In combination, a mop head comprising a trapezoidal plate, said plate being divided into two sections on a line perpendicular to the parallel sides of the trapezoid, said sections being hinged together, and a ring-like mop having a flexible binding adapted to be engaged by the ends of said trapezoidal plate.

In testimony whereof I have affixed my signature in presence of two witnesses.

JOHN RUDD VAN DYNE.
